UNITED STATES PATENT OFFICE.

GEORGE S. GROVES, OF ALEXANDRIA, VIRGINIA, ASSIGNOR TO SHELTON H. GROVES, OF ALEXANDRIA, VIRGINIA.

WAVE-MOTOR.

1,323,182.

Specification of Letters Patent.

Patented Nov. 25, 1919.

Application filed June 29, 1918. Serial No. 242,617.

To all whom it may concern:

Be it known that I, GEORGE S. GROVES, a citizen of the United States, residing at Mt. Ida, Alexandria, in the county of Alexandria and State of Virginia, have invented certain new and useful Improvements in Wave-Motors, and I do hereby declare the following to be a full, clear, and exact description of the invention, such as will enable others skilled in the art to which it appertains to make and use the same.

This invention relates to motors, and more particularly to wave motors.

It is one of the objects of the present invention to provide mechanism for deriving power from wave action in bodies of water, and to provide such a device as will operate with the maximum efficiency by the peculiar relation of the elements of the machine and utilization of elements operative with minimum friction and resistance. It is another object of the invention to provide for the translation of the motion of waves into continuous rotary movement, and also to provide for the adjustment of the wave receiving mechanism to compensate for variation of the level of the main body of water to tidal action.

With the above and other objects in view as will be manifest to those versed in the art, the invention consists in the construction, the combination, and in details and arrangement of parts more particularly set forth in the following specification relative to the embodiment of the invention, illustrated in the accompanying drawing, in which—

Figure 1 is a side elevation of the apparatus, and

Fig. 2 is a plan view broken away to indicate indefinite length.

The invention is illustrated as comprising a pier structure consisting of a suitably arranged group of piles 2 forming for instance a rectangle in outline, and within the area of which there is arranged an appropriately constructed frame 3 of metal, preferably including at its lower front portion a horizontal I beam 4 extending longitudinally beyond the front row of piles 2, the end piles being provided with vertical guide rails or I beams 5—5 between which the horizontal frame beam 4 is vertically movable and is guided. Supported upon the upper flange or face of the horizontal beam 4 there is a suitable

flooring 6 inclined upwardly and rearwardly, the rear edge of the flooring 6 terminating approximately vertically over a shaft 7 extending longitudinally of the frame 3 and supported in numerous bearings 8 appropriately arranged in the frame 3.

For the purpose of taking the power from waves, the frame 3 is preferably adjustable so as to lower its floor 6 so that its front and lower edge will dip somewhat below the upper portion of the waves, the latter being cut as they impinge against the floor and thence roll upwardly, discharging over the rear edge of the floor toward a back-stop or plate 10 inclined downwardly and forwardly and appropriately mounted on the frame 3, the lower edge of the back stop or plate 10 terminating adjacent to the perimeter of a wheel structure preferably in the form of an over-shot water wheel generally indicated at W, and which is provided by reason of the brackets or supporting bearings 8 into a number of axially aligned sections as clearly seen in Fig. 2.

The body of water moving upwardly along the floor is permitted to fall from the rear edge of the same on to the rear upper portion of the over-shot water wheel W and this is thereby rotated through the pressure of the water. Preferably the wheel is of such diameter as not to be submerged in the main body of water, and thereby is not subjected to untoward resistance.

Means for transmitting the power from the water wheel to any suitable point may be of appropriate construction and form and as here shown comprises a sprocket wheel 11 mounted on one end of the shaft 7 projecting beyond the steel frame, this sprocket wheel driving a sprocket chain 12 which is extended upwardly over a sprocket wheel 13 which is mounted on the shaft 14 to be driven by the power derived from the wave action, this shaft permitting the distribution of the power as may be desired. To compensate for variations of level owing to tidal action, the frame is adapted to be vertically adjusted, and therefore the effective length of the sprocket belt or chain 12 is capable of being varied or adjusted through means of a tightening wheel 15 mounted on the sliding bearing block 16 which may be suitably clamped or secured in its various lateral positions, with respect to the driven shaft 14.

The driven mechanism, as well as means for adjusting the position of the frame 3 are preferably arranged at the top of the pier structure and may be inclosed in a house indicated at H in which the operators or attendants may be protected from the elements and be within convenient reach of the adjusting mechanism. To change the position of the frame 3 to compensate for tide levels, appropriate means may be utilized, and as here shown comprises a series of vertical screws 18 attached at their lower ends to the floor 6, and at their upper ends passing through suitable lifting nuts 19 which when rotated will cause the vertical movement of the screw rods 18 and thereby adjust and lock the floor frame 3 as may be desired.

As shown, the end edges of the flooring 6 are provided with upright end flanges or walls 6^a serving the purpose of preventing relatively longitudinally moving waves from sweeping off of the ends of the flooring, and a similar purpose is provided in connection with the movement of the water over the wheel W by arranging at each end thereof flanges or disks w.

What is claimed is:

1. In a wave-motor, a frame having an inclined wave collecting floor, an over-shot water wheel journaled horizontally beneath the upper end of floor so that the water im-

peled up the floor falls on the rear upper portion of the wheel, and a back-stop arranged at the rear of the floor and having its lower edge adjacent to the wheel perimeter.

2. In a wave-motor, a frame having an inclined wave collecting floor, an over-shot water wheel having the usual circular end pieces journaled horizontally beneath the upper end of floor so that the water impelled by the floor falls on the rear upper portion of the wheel, a backstop arranged at the rear of the floor intermediate said end pieces and having its lower edge adjacent to the wheel perimeter, the lower part of the wheel being normally maintained above the surface of the main body of water.

3. In a wave-motor, a frame having an inclined wave collecting floor, an over-shot water wheel journaled horizontally beneath the upper end of floor so that the water impelled up the floor falls on the rear upper portion of the wheel, an inclined backstop arranged at the rear of the floor and having its lower edge adjacent to the wheel perimeter said wheel being supported by the floor, a pier structure in which the frame is guided for vertical movement, and means for vertically adjusting the floor, the backstop and the wheel in said pier structure.

In testimony whereof I affix my signature.
GEORGE S. GROVES.
